VAPORIZING DEVICE

John H. Seitz, Woodhaven, N. Y., assignor of
one-half to Joseph Fuhringer, Lake Ronkon-
koma, N. Y.

Application June 17, 1938, Serial No. 214,365

6 Claims. (Cl. 261—94)

This invention relates to improvements in vaporizing devices and is particularly concerned with devices adapted to vaporize liquid fuel for internal combustion engines, oil burners or the like.

It is an object of the invention to provide a device capable of converting liquid fuel into finely divided vapor readily capable of combustion whereby utmost energy may be obtained from such fuel.

A further object of the invention is to provide a device which is adapted to vaporize relatively heavy or high boiling motor fluids, such as kerosene and fuel oil, without necessity of employing heat to assist or effect such vaporization.

A further object of the invention is to provide a device which, when associated with the suction side of a blower, an intake manifold, or the like, is readily responsive to the suction therefrom and will feed thereto in predetermined volume liquid fuel in a finely divided vaporous condition.

Still another object is to provide a vaporizing device having a novel arrangement of air ducts through which air may be drawn into the vaporizing chamber and into the liquid chamber preferably beneath the level of the liquid therein whereby to positively force the liquid into the vaporizing chamber and whereby to regulate the character or degree of its vaporization.

Another object is to provide a vaporizing device which is of simple and compact construction and positive and durable in operation.

Other and further advantages of the invention will be apparent from the following detailed explanation thereof taken in conjunction with the accompanying drawings wherein a preferred embodiment of the principles of the invention has been selected for exemplification.

In the drawings, Fig. 1 is a longitudinal sectional view of a vaporizing device embodying the principles of the herein invention.

Fig. 2 is a fragmentary section taken along line 2—2 of Fig. 1 and looking in the direction of the arrows.

Fig. 3 is a sectional view taken along line 3—3 of Fig. 1 and looking in the direction of the arrows.

Fig. 4 is a side elevational view of the device illustrated in Fig. 1 shown in association with the intake manifold of an internal combustion engine; and

Fig. 5 is a side elevational view of the device of Fig. 1 shown in association with the suction side of a blower as for an oil burning furnace or the like.

Referring more particularly to the drawings wherein like numerals refer to like parts, a housing indicated generally at A includes at opposite ends thereof an elongated vaporizing compartment 10 and a liquid compartment 12. Packed in vaporizing compartment 10 and extending substantially throughout the length thereof is a mass of steel wool or other equivalent material which is capable of dispersing the liquid into an extremely finely divided vaporous condition during its passage therethrough. The mass of steel wool 14 or other material having equivalent characteristics under the conditions herein also operates as a filtering medium for the liquid fuel. Shoulders 16 or other suitable means may be provided interiorly of the vaporizing chamber 10 to support at opposite ends thereof screens 18, which in turn serve to support and compact therebetween the mass of dispersing and filtering material 14.

As clearly shown in Fig. 1, liquid chamber 12 is positioned at the bottom of cylindrical housing A and directly beneath and in open communication with the vaporizing chamber 10. Liquid is introduced to the chamber 12 through inlet connection 20 and the liquid therein may be maintained at a predetermined level by means of a novel float valve arrangement including the disc float member 22 which bears upon a lever 24 which in turn pivotally supports and suspends a valve stem 26 carrying a valve 28 which is adapted to operate with a seat 30 formed in the liquid feed line 20.

Disposed axially of the housing A and extending axially throughout the length of the vaporizing chamber 10 and liquid chamber 12 is an internal flue indicated generally at 32 carrying at its lower end a yoke member 34 which receives the valve stem 36 of a safety or release valve 38 normally urged in seated position upon the end 40 of the flue 32 by means of a tension spring 40. Safety valve 38 serves to readily release pressure resulting from any backfire or the like whereby such disturbances will not deleteriously affect vaporizing chamber 10 or other parts of the apparatus.

That flue 32 extends centrally through liquid chamber 12 so that the liquid chamber is disposed circumferentially of the flue makes possible the novel float valve arrangement wherein the ringlike float 22 may be disposed annularly of the exterior wall of the flue 32 and be guided thereby.

Disposed circumferentially of the housing A at the end thereof forming the liquid compart-

ment 12 and the lower portion of the vaporizing compartment 10 is a double walled skirt 41 between the walls of which are provided a plurality of pairs of tubular air ducts 42 and 44 communicating with vapor chamber 10 and liquid chamber 12, respectively. For this purpose, the outer wall of vaporizing chamber 10 is suitably apertured as at 46 and the outer wall of liquid chamber 12 is suitably apertured as at 48. It will be noted that the apertures 48 in the wall of the liquid chamber preferably are disposed beneath the normal level of the liquid therein whereby the air draft through the ducts 44 will bubble through the liquid whereby to initiate some breaking up of the liquid when it is drawn into the vaporizing chamber.

The outer ends of the tubular air ducts 42 and 44 open upwardly of the liquid chamber 12 and preferably terminate in a single plane whereby to be more readily associated with a slide valve in the form of an apertured collar 50 manually rotatable by the projection 52 and supported upon the skirt 41 by means of lugs 54 whereby reciprocal or rotary movement thereof may vary registration of the apertures with the free ends of the various pairs of air ducts 42 and 44 to control the admission of air thereto.

A closure 56 at the upper end of housing A supports a tubular outlet 58 for the vaporous products issuing from vaporizing chamber 10. As clearly shown in Fig. 1, the tubular outlet 58 has a portion 60 thereof telescopically arranged with respect to internal flue 32 whereby to provide a reversely curved flow path for the exiting vapors as indicated by the arrows in Fig. 1. This arrangement provides a baffle for the exiting vapors and also offsets or removes the vapor outlet from the vaporizing chamber 10 and associates the vapor outlet with the flue 32 so that in the event of backfire or the like the pressure will be released through operation of safety valve 38 disposed at the opposite end of flue 32 and will not carry into the vaporizing chamber 10. A throttle or feed valve 62 to regulate withdrawal of vapors is disposed internally of tubular outlet 58.

In the operation of the device above described, the outlet end thereof may be suitably connected to the inlet manifold of an internal combustion engine indicated generally at B in Fig. 4 or to the suction side of a blower as indicated generally at C in Fig. 5 and the liquid inlet end thereof suitably connected to a fuel supply.

Slide valve 50 may be adjusted to the extent necessary to control the admission of air to air ducts 42 and 44 communicating with vaporizing chamber 10 and liquid chamber 12, respectively, and in response to the suction exerted by the intake manifold B or the blower C, predetermined quantities of liquid and air will be drawn into the vaporizing chamber 10 and into the steel wool or other packing material 14 whereby the liquid will be broken up into a finely divided vaporous condition, the vaporous mixture thence passing to the outlet tube 58 and its withdrawal into the manifold B or the blower C regulated by means of throttle valve 62. Valve 30 disposed in liquid inlet 20, being responsive to the liquid level in chamber 12, will function to maintain the liquid in chamber 12 at any desired predetermined level preferably short of lower screen 16 which supports the mass of steel wool or equivalent material 14.

It will be apparent that if the filtering or dis-

persing material 14 becomes contaminated or if for other reasons it is desirable to remove the same, closure 56 may be removed from the housing A, upper screen 16 unseated and the mass 14 readily withdrawn and replaced or replenished and the device again assembled by reverse steps. Provision of the steel wool or mass of equivalent material 14 makes it possible to effect a fine vaporization of relatively heavy fuels on the order of kerosene, fuel oil or the like, without the necessity of applying added heat to effect or assist in effecting vaporization thereof. In this respect the device is simpler in construction and possesses fewer parts than prior devices and has been found to be extremely efficient in opera- 15

10 It is understood that the device herein illustrated and described is exemplary only of the principles of the invention which are capable of such modification as comprehended within the 20 scope of the following claims.

What I claim is:

1. A vaporizing device comprising, a housing forming at one end a vaporizing chamber and at its other end a liquid chamber in open communication with said vaporizing chamber, a flue disposed internally of said housing and extending through said vaporizing and liquid chambers, one end of said flue communicating with the outlet end of said vaporizing chamber, a vapor exit tube telescopically arranged in said end of said flue whereby to provide a reversely curved flow path for the exiting vapors and a pressure release valve disposed in the opposite end of said flue. 35

2. A vaporizing device comprising, a housing forming at one end a vaporizing chamber and at its other end a liquid chamber in open communication with said vaporizing chamber, a mass of steel wool disposed in said vaporizing chamber and in the path of the liquid whereby to vaporize the liquid in the cold without the application of heat, a flue disposed internally of said housing and extending through said vaporizing and liquid chambers, one end of said flue communicating with the outlet end of said vaporizing chamber and a vapor exit tube telescopically arranged in said end of said flue whereby to provide a reversely curved flow path for the exiting vapors. 50

3. A vaporizing device comprising, a cylindrical housing forming at one end thereof an elongated vaporizing chamber and at the other end thereof a liquid chamber in open communication with said vaporizing chamber, a flue disposed internally of said housing and extending through said vaporizing and liquid chambers, one end of said flue communicating with the outlet end of said vaporizing chamber, a vapor exit tube telescopically arranged in said end of said flue whereby to provide a reversely curved flow path for the exiting vapors, a pressure release valve arranged in the opposite end of said flue, means for maintaining the liquid in said liquid chamber at a predetermined level including a ring-like float valve disposed annularly of and guided by said internal flue, and a plurality of air ducts disposed circumferentially of said housing and communicating with said vaporizing and said liquid chambers to admit air thereto. 65

4. A vaporizing device comprising, a housing forming a vaporizing chamber having a vapor outlet and a liquid inlet, a tubular member positioned axially within said vaporizing chamber, a mass of steel wool disposed annularly of

said tubular member and within said vaporizing chamber in the path of the liquid whereby to vaporize the liquid in the cold without the application of heat, and a telescopically arranged 5 vapor outlet flue communicating with said vaporizing chamber outlet whereby to provide a reversely curved flow path for the exiting vapors.

5. A vaporizing device comprising, a vaporizing compartment having a liquid inlet and a vapor outlet, a flue communicating with said vapor outlet, a vapor exit tube telescopically arranged in one end of said flue whereby to provide 10

a reversely curved flow path for the exiting vapors, and a pressure release valve disposed at the opposite end of said flue.

6. A vaporizing device comprising, a vaporizing compartment having a liquid inlet and a vapor outlet, a flue communicating at one end with said vapor outlet and offset from said vaporizing compartment, a vapor exit tube telescopically arranged in the vapor inlet end of said flue to baffle the incoming vapors, and a pressure release valve disposed at the opposite end of said flue. 5 10
